GEORG ULLRICH, OF MAGDEBURG, GERMANY, ASSIGNOR TO FRIED. KRUPP GRUSON-WERK AKTIENGESELLSCHAFT, OF MAGDEBURG-BUCKAU, GERMANY

MAGNETIC SEPARATION AND DISCHARGE OF BULK GOODS

Application filed December 8, 1925, Serial No. 74,141, and in Germany December 12, 1924.

The present invention relates to means for transporting bulk goods of the type employing conveyor bands which are supported by rollers in such a manner as to form a trough, so that the bulk goods form a deeper layer in the centre than at the edges. If during the transport magnetic substances are to be separated from such goods or material, the discharge drum is formed into a magnetic separation drum, and in such drums as hitherto constructed the same magnetic power of attraction has been provided throughout the whole width of the conveyor band. It has been necessary, therefore, to use an excitation current sufficiently strong to ensure that, even in the centre of the band, where the material forms the deepest layer, the magnetic substances should be attracted in a reliable manner, whilst for the thinner layer of material at the edges of the band, a smaller excitation current would have been sufficient. Such separation drums involve, therefore, higher cost as regards purchase and current than is necessary.

According to the present invention these drawbacks are avoided by constructing the separation and discharge drum in such a manner that the magnetic field strength decreases from the centre of the conveyor band towards its edges. This end may be attained in various ways, for example, the field gaps of the drum could either be arranged transversely of the axis, that is to say extend circumferentially, or they could be formed into slots extending parallel to the axis. In the former case the magnetic strength in the circumferential gaps decreases from the centre of the band towards its edges. In the latter case bar-shaped poles are formed in such a manner as to constitute between them field gaps of a width increasing from the centre of the band towards its edges.

With the improved construction of drum, a more reliable attraction of the magnetic substance throughout the whole width of the band can be ensured with smaller conductors and current consumption than with drums as hitherto proposed.

In order that the invention may be clearly understood and readily carried into effect, it

will be described more fully with reference to the accompanying drawings, in which:

Figures 1 and 2 are longitudinal views, partly in section, of two forms of magnetic separating and discharging drum in which the field gaps are circumferential.

In the form of the invention shown in Figure 1 pole discs 1 are mounted on a magnet core 2 and enclose between them excitation coils 3 and 4, the central coil 3 has either more windings than the lateral coils 4, or it is excited by a stronger current than the latter, with the result that there is a greater force of attraction over the central field gap than over the lateral field gaps. In this case either all pole discs and gap widths could be the same or, for the purpose of still further increasing the field strength of the central field, its pole discs could be made wider than the outer ones, and its gap width could also be made smaller than that of the outer fields.

In the example depicted in Figure 2, six pole discs 1 are mounted on the magnet core 2, the two central ones being the widest and the others narrower than these. Accordingly a stronger field exists between the two central pole discs than that between the adjoining discs, and these two fields are stronger than the end fields. The two outer pole discs of each side could be made longitudinally adjustable on the magnet core by means of the screws 5 or in some other manner, for the purpose of regulating the strength of the fields.

The separation and discharge drum may be suitably enclosed in a protective casing 10.

What I claim is:

1. A magnetic separator and discharge drum for conveyor bands comprising, a core having a plurality of circular pole disks and an exciting winding, the pole disks nearer the middle of the drum being wider than those nearer the outside, whereby a magnetic field of continuously increasing strength from the outside toward the center of the drum is produced.

2. In a magnetic separator and discharge drum for conveyor bands, a core having pole pieces, defining a plurality of gaps, distributed over the peripheral surface of the drum

near its edges as well as at the center thereof, and means for creating a magnetic field extending across said gaps, said pole pieces being so arranged as to provide a continuous increasing field strength from the edges toward the center of the drum.

3. In a magnetic separator and discharge drum for conveyor bands, a core, an exciting winding on said core, a plurality of pole disks distributed along said core and forming circumferential field gaps, the construction being such that a stronger field is produced between the pole disks located near the center of said core than between those located near its ends.

4. In a magnetic separator and discharge drum for conveyor bands, a core, a plurality of pole disks on said core forming circumferential field gaps, and an exciting winding on said core, the amperes turns of said exciting winding between the pole disks nearest the middle of said core being greater than between the pole disks nearer the ends of said core.

5. A magnetic separator and discharge drum for conveyor bands comprising, a core having a plurality of circular pole disks and an exciting winding, the pole disks near the middle of the drum being wider than those nearer the outside, said lateral pole disks furthermore being mounted in an axially adjustable manner.

The foregoing specification signed at Berlin, Germany, this 23rd day of November, 1925.
